EDWARD LOUIS TAYLOR, OF HARTFORD, CONNECTICUT, ASSIGNOR, BY
MESNE ASSIGNMENTS, TO WILLIAM C. GOODWIN.

Letters Patent No. 100,466, dated March 1, 1870.

IMPROVEMENT IN TOYS.

The Schedule referred to in these Letters Patent and making part of the same.

To all whom it may concern:

Be it known that I, EDWARD L. TAYLOR, of Hartford, in the county of Hartford, and State of Connecticut, have invented a new Improvement in Toy "Perpetual Grinder;" and I do hereby declare the following, when taken in connection with the accompanying drawings and the letters of reference marked thereon, to be a full, clear, and exact description of the same, and which said drawings constitute part of this specification, and represent in

Figure 1, a top view;

Figure 2, an edge view; and in

Figure 3, a central section.

This invention relates to an improvement in the construction of paper wind-wheels, such as are employed in toys for the purpose of imparting power to operate the same.

In such wheels, as heretofore constructed, a great difficulty is experienced from the fact that after a little use the edges of the wheels will sag or bend downward, which destroys the wheel for the purpose designed.

The object of my invention is to sustain the edge of the wheel so that it will not sag, and consists in constructing the wheel with a rim affixed to each of the fans, and shortening the rim so as to diminish its circumference, and thereby raise the edge of the wheel above the center.

A is the center of the wheel, with several arms, B, extending out to a rim, C, the space between each of

the arms being cut so as to leave the material cut on every arm, which said cut part, D, is turned downward, as seen in figs. 1 and 2. This is cut from a single piece of paper or pasteboard, and if the surface be left flat, the wheel being supported only on the hub E in the center, the edges will soon sag and the wheel become unfit for use. To prevent this I shorten the rim of the wheel by bending the rim as at a, forming two angles, which shortens the rim by so much as the said two angles, and to make this more secure I prefer to coat the bent part a with glue or other sizing, which sets it in that position.

Substantially the same result may be attained by cutting the rim at one or more places, and overlapping the ends so as to contract the rim.

The result of thus shortening the rim is to curve or "dish" the wheel, as seen in fig. 3, which prevents all possibility of the wheel sagging or working out of shape.

I claim as my invention—

In the construction of paper wind-wheels for toys, shortening the rim C by overlapping or bending the same, as at a, so as to curve and support the wheel, substantially in the manner and for the purpose described.

EDWARD LOUIS TAYLOR.
